UNITED STATES PATENT OFFICE.

DUDLEY D. FOWLER, OF KANSAS CITY, MISSOURI.

GAS-MIXER.

1,178,509.

Specification of Letters Patent. Patented Apr. 11, 1916.

Application filed September 30, 1915. Serial No. 53,400.

To all whom it may concern:

Be it known that I, DUDLEY D. FOWLER, a citizen of the United States, residing at Kansas City, in the county of Jackson and 5 State of Missouri, have invented certain new and useful Improvements in Gas-Mixers; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to a gas mixer and more particularly to a device of that character comprising a chamber into which air and gas are delivered separately to commingle and form a fuel mixture, the object 20 of the present invention being to provide means for automatically regulating the admission of air to the chamber in proportion to the intake of gas for any opening of the gas valve. In accomplishing this object I 25 have provided improved details of structure, the preferred forms of which are illustrated in the accompanying drawings, wherein:

Figure I is a side elevation of a mixer containing my improvements, the dotted 30 lines indicating a maximum intake of gas and air. Fig. II is a central longitudinal section of the same. Fig. III is a plan view of the same. Fig. IV is a cross section on the line IV—IV, Fig. I. Fig. V is a longitudinal central section of part of the mixing 35 chamber, showing the air valve open. Fig. VI is a cross section on the line VI—VI, Fig. I, particularly illustrating the cam member for actuating the air valve from 40 the gas valve stem.

Referring more in detail to the drawing: 1 designates a mixing chamber which may be suitably mounted on a burner conduit, indicated by the tube 2 in any suitable manner 45 and having a closed outer end 3, provided with a central aperture 4 into which is threaded the neck 5 of a valve housing 6, and having an aperture 7 therein provided with a tapered seat 8, through which air 50 may be admitted to the mixer.

The valve housing 6 has a bore 10 extending therethrough and provided with an enlargement 11 in its neck, within which is seated a plug 12, containing a tapered channel 13 for seating a needle valve 14, that is formed on a stem 15. The stem 15 is con-

tained within the longitudinal bore 10 and has a triple thread connection with the wall of the bore, in order to accelerate movement of the needle valve to and from its seat when 60 the stem is revolved, the outer end of the stem being equipped with a suitable handle 16 whereby the valve may be manipulated.

The housing 6 is provided with a nipple 18, containing a bore 19 that extends into 65 the stem to communication with the enlargement 11, of the bore 10, and is preferably extended through the nipple at an angle in order to deliver in the direction of the mixer and facilitate flow of gas into the mixing chamber, the nipple being provided with a threaded neck 20 to which a suitable tube or conduit may be attached. The valve housing neck 5 is preferably provided with a lock nut 21 for fixing the housing to the 70 mixer 1 and with a gland 22 which threads onto the outer end of the housing to confine packing of a suitable nature about the valve stem and prevent leakage.

Pivots on an ear 23, on the 80 housing 6, is a lever 24, having a curved neck 25 at its forward end, provided with a downwardly facing valve head 26 that is adapted to seat in the tapered seat 8 of the mixing valve and is provided with a cap 28 85 that lies over the valve to completely close the air port, the channel housing being built up by a boss 29 to form a flat bearing surface for the cap 28 and an even, effective seat for the valve head 26.

The rear end of the lever 24 is projected 90 into a cam slot 30 in a segment 31, having a hub 32 fixed to the valve stem 15 by a set screw 33 or the like, the cam slot being circular, but eccentric relative to the stem 15, in order to move the end of the arm 24 toward or from the valve stem, as the latter 100 is revolved and thereby rock the arm on its pivotal mounting to move the air valve head toward or from its seat according to the direction of the movement of the valve stem. The segment 31 is adjustably mounted on the valve stem 15 by means of the set-screw so that the segment may be moved toward and from the fulcrum of the lever 105 24, and the slot 30 extends entirely through the segment so that the segment may be moved over the end of the lever for varying degrees, in order to vary the opening of the air valve port for like rotary movement of the valve stem. By providing for the adjustment of the segment on the valve stem 110

and relative to the lever arm, it is apparent that where a greater or less amount of air is required for a given quantity of gas, the segment may be moved along the valve stem 5 in the proper direction to vary the proportionate movement of the air valve, so that a greater movement of the stem is required for a certain quantity of air when the segment is in an outer position, than is required 10 when the segment is in an inner position, the opening through the segment permitting the latter to slide along the lever arm to provide a wide range of adjustment.

Assuming that the parts are constructed 15 and assembled as described, with the neck 20 of the valve housing connected with a source of gas supply (not shown), it is apparent that when the needle valve is in closed position, flow of gas to the mixer is 20 shut off and that, with the segment 31 properly arranged on the gas valve stem, the air valve will seat snugly against the tapered seat of the air port. When it is desired to admit a fuel mixture to the mixer, for sup- 25 plying a burner or the like, the gas port is opened by turning the handle 16 to move the stem on its threaded mounting and withdraw the needle valve from its seat, to form an opening to the tapered channel 13 so 30 that gas may be delivered to the mixing chamber.

As the segment 31 is fixed rigidly to the valve stem, movement of the stem carries the segment about with the stem, and as 35 the air valve lever 24 is anchored against rotary movement, the segment moves the free end of the lever and rocks the lever inwardly by frictional engagement of the sides of the cam slot with the end of the 40 lever. This pivotal movement of the air valve lever rocks the valve head 26 upwardly upon downward movement of the opposite

end of the lever and removes the head from its seat, forming an opening into the mixing chamber through which air may pass to co-mingle with the gas admitted through the valve housing, to form a fuel mixture. It is apparent that any movement of the valve stem will effect a like movement of the air valve, so that as the opening of the gas port 45 is increased the opening of the air port is increased in like proportion, to effect a proper balance of the gas and air for any degree of opening of the gas port.

Having thus described my invention, what 50 I claim as new therein, and desire to secure by Letters-Patent, is:

1. A gas mixer comprising gas and air intake ports, a valve for controlling one of said ports, and comprising a rotary stem, 60 a member adjustably mounted on said stem and having a cam slot extending therethrough, a valve for controlling the other port, and a lever connected with said last named valve and having an arm slidably 65 projected into the cam slot in the member on said stem, whereby the said member may be moved along the arm to vary the lever- age length of the arm.

2. A gas mixer comprising gas and air 70 intake ports, a valve for controlling the gas port, comprising a rotary stem, a segment having a hub mounted for longitudinal ad- 75 justment on the stem, and having a cam slot, a valve for controlling the air port and com- prising a pivotally mounted lever, having an arm slidably projected into the slot in 80 said segment, and a handle for said valve stem whereby the stem and the segment are operated synchronously to effect synchro- nous operation of said valves.

In testimony whereof I affix my signature.

DUDLEY D. FOWLER.
